DESIGN FOR A MATCHING TOY

Samuel L. Beder, Bronx, N. Y.

Application October 6, 1945, Serial No. 122,581

Term of patent 7 years

(Cl. D34—15)

To all whom it may concern:

Be it known that I, Samuel L. Beder, a citizen of the United States, a resident of Borough of Bronx, city of New York, county of New York, and State of New York, have invented a new, original, and ornamental Design for a Matching Toy, of which the following is a specification, reference being had to the accompanying drawing, forming part thereof.

Fig. 1 is a front elevational view of a matching toy showing my new design.

Fig. 2 is a top plan view; and

Fig. 3 is a side elevational view thereof.

I claim:

The ornamental design for a matching toy, substantially as shown.

SAMUEL L. BEDER.
